CLAIM

The ornamental design for a tamper evident closure, as shown and described.

DESCRIPTION

FIG. 1 is an upper perspective view of a tamper evident closure;

FIG. 2 is an enlarged perspective view taken from within portion “2” of FIG. 1;

FIG. 3 is a front view taken from within portion “3” of FIG. 1;

FIG. 4 is a left side view taken from within portion “4” of FIG. 1;

FIG. 5 is a right side view taken from within portion “5” of FIG. 1; and,

FIG. 6 is a top view taken from within portion “6” of FIG. 1.

The dash-dash broken lines represent portions of the tamper evident closure that form no part of the claimed design. The dot-dash broken lines represent the designation of enlargement views and form no part of the claimed design.

1 Claim, 4 Drawing Sheets
